UNITED STATES PATENT OFFICE.

JOSEPH M. CRUCET, OF NEW YORK, N. Y.

DESIGN FOR A FAN, STAND, AND CASING.

48,711.

Specification for Design.

Patented Mar. 14, 1916.

Application filed September 2, 1915. Serial No. 48,725. Term of patent 7 years.

To all whom it may concern:

Be it known that I, JOSEPH M. CRUCET, a citizen of the United States, residing in New York, in the county of New York and State of New York, have invented a new, original, and ornamental Design for a Fan, Stand, and Casing, of which the following is a specification, reference being had to the accompanying drawing, forming part thereof, in which—

Figure 1, represents a front view of a fan, stand and casing embodying this invention. Fig. 2 is a side view of the same.

I claim:

The ornamental design for a fan, stand and casing, as shown.

JOSEPH M. CRUCET.

Witnesses:

CHRISTIAN H. ALMSTAEDT,
WILLIAM MILLER.
